UNITED STATES PATENT OFFICE.

URIAH E. MILLER, OF HEILIG'S MILLS, NORTH CAROLINA.

RUNNING-GEAR.

SPECIFICATION forming part of Letters Patent No. 406,226, dated July 2, 1889.

Application filed October 12, 1888. Serial No. 287,891. (No model.)

To all whom it may concern:

Be it known that I, URIAH E. MILLER, of Heilig's Mills, in the county of Rowan and State of North Carolina, have invented a new and Improved Running-Gear, of which the following is a full, clear, and exact description.

The invention relates to that class of wagons in which the reaches are made longitudinally adjustable and so constructed as to effect the turning of the wagon within a small compass.

The object of the invention is to furnish a wagon of this character in which the hinge or pivot of the reach may always be central of the front and rear axles, and in which the pivoted reach may be removed and the rigid one alone used.

The invention consists in the novel construction and combination of parts, as hereinafter particularly described, and pointed out in the claims.

Reference is to be had to the accompanying drawings, forming a part of this specification, in which similar letters of reference indicate corresponding parts in all the figures.

Figure 1 is a plan view of a running-gear embodying my invention. Fig. 2 is a longitudinal central section on line xx ; Fig. 3; and Fig. 4 is an end elevation.

On the axles A A' are mounted the usual sand-boards B B' and body-bolsters C C'. Connecting the front and rear running-gear are the main rigid reach D and auxiliary reach E, the latter being centrally pivoted or hinged, as at E', to flex or bend laterally when the wagon is cramped, as in Fig. 1.

The main rigid reach D is held at its front end by the front king-bolt F and at its rear by the rear king-bolt F', the reach passing between the sand-boards and the axles. The rear end of reach D is formed with a series of apertures d, through any one of which the rear king-bolt F' passes. By this construction the reach D is adjustable to a shortened or lengthened position of the wagon.

On the reach D are held collars d', formed with hooks d², or equivalent devices, for engaging the brace-chains d³, which extend from each hook d² to the bolsters C C'. The rear collar d' is adjustable longitudinally on the

reach that its position may be changed in ac-

cordance with the adjusted position of the reach.

The hinged auxiliary reach E is held at its front end in a keeper G on the under side of axle A, and is formed at its front end with a series of apertures e similar to the apertures d in the rear end of reach D, through any one of which apertures e the front king-bolt F may be passed, while the rear end of the reach E is loosely supported in a keeper G' to have a free longitudinal movement in said keeper between two friction-rollers H. The rear king-bolt F' does not pass through the rear end of reach E.

The rear member of auxiliary reach E is provided an additional guide and support in its movements by the plates i, which are provided with friction-rollers i' and are secured to the spaced ends of the rear hounds I I, between which plates and rollers the reach lies. The front member of the reach E has an additional support in a keeper j, secured to the under side of the frame J, which is carried by the front gear, and will be presently fully described.

Braces I' I' are secured at one end to the hounds I and at their other ends to the rear axle or sand-board.

The frame J is secured to the front gear between the axle and sand-board thereof and projects rearwardly therefrom, and acts as a substitute for front hounds for main reach D. The side members j' of the frame are connected at the rear ends with the spaced cross-bars j² and at the front are united by a brace-rod j³. The spaced cross-bars j² of frame J form a support for main reach D, the latter lying between the same, as best shown in Fig. 2.

By making the reaches adjustable, respectively, at the front and rear ends the hinge or pivot of the auxiliary reach may be maintained centrally of the front and rear axles, whereby the rear wheels will always track the front ones in turning, and thus the wagon may be turned within a shorter compass than if the pivot were not in a central position, as in the latter case the rear wheels would not track the front ones.

The auxiliary reach E may be removed, if

desired, and the rigid one D substituted; or a longer rigid one may be substituted.

Having thus described my invention, what I claim as new, and desire to secure by Letters 5 Patent, is—

1. The combination, in a running-gear, of the main rigid reach D, having its one end adjustable, the auxiliary reach E, hinged centrally to flex in a lateral direction and adjustable at the end opposite the adjustable end of the reach D, collars d^2 , formed with hooks d^2 and secured to reach D, one of the collars being adjustable thereon, and the chains d^3 , extending from the hooks d^2 to the body-bolsters, substantially as described.

2. The combination, in a running-gear, and with the axles and bolsters thereof, of the main reach D, pivotally secured at each end and longitudinally adjustable at one end, the frame 15 J, secured to the front gear and between the

spaced cross-bars j^2 of which the reach D lies, the auxiliary reach E, hinged at its center to flex laterally and made adjustable at one end, the hounds I, spaced at their ends, the plates i , uniting said spaced ends, and the friction-rollers i' , substantially as described.

3. The combination, in a running-gear, of a main rigid reach D, adjustable longitudinally at its rear end, the auxiliary reach E, hinged at its center to flex laterally and adjustable 30 longitudinally at its front end and having a free endwise movement at its opposite end, the keepers G G', secured to the under side of the axles, and the friction-rollers H, between which the free end of reach E is guided, substantially as described.

URIAH E. MILLER.
